UNITED STATES PATENT OFFICE.

HERMAN ELSAS, OF NEW YORK, N. Y.

MULTIPLEX FOURDRINIER.

Application filed May 7, 1924. Serial No. 711,532.

To all whom it may concern:

Be it known that I, HERMAN ELSAS, a citizen of the United States, and a resident of the city of New York, in the county of New York and State of New York, have invented certain new and useful Improvements in Multiplex Fourdriniers; and I do hereby declare that the following is a full, clear, and exact description of the same, reference being had to the accompanying drawings, and to the numerals of reference marked thereon, which form a part of this specification.

This invention relates more particularly to a paper making machine wherein a multiplex sheet of paper may be readily and cheaply produced by means of a plurality of Fourdrinier type paper making machines disposed at different elevations with the wires running in the same or in different directions to permit the webs of paper to be brought into contact and felted together either at the couch rolls or at the first press rolls depending upon the relative positions of the Fourdriniers and the direction of movement of the wires.

It is an object of this invention to remove webs of paper from a plurality of Fourdriniers by means of a plurality of felts.

It is also an object of the invention to provide a method of producing a sheet of paper by felting together webs of paper by using a plurality of Fourdriniers positioned one above the other.

It is a further object of this invention to arrange a plurality of Fourdriniers one above the other so that the Fourdrinier wires will conduct paper webs into the fields of operation of either the couch rolls of one of the Fourdriniers or the first set of press rolls.

It is furthermore an object of the invention to produce a sheet of paper with the two sides of different colored paper having a fine formation and the other qualities which can only be derived from Fourdrinier type of machines.

It is an important object of this invention to provide a machine adapted to readily make paper constructed with opposite sides of different grades and finish of paper and of different colors if desired, said paper being readily produced by the novel arrangement of a plurality of Fourdriniers positioned at different elevations with each Fourdrinier having a felt co-acting there-

with to pick up the paper webs and conduct the same through couch rolls and press rolls to a dryer.

It is finally an important object of this invention to provide a machine and process adapted to form a product which is extremely strong and flexible.

Other and further important objects of this invention will be apparent from the disclosures in the specification and accompanying drawings.

The invention (in a preferred form) is illustrated in the drawings and hereinafter more fully described.

On the drawings: Figure 1 is a side elevational schematic of a multiplex Fourdrinier machine embodying the principles of this invention showing the floors in section.

Figure 2 is a schematic of a modified arrangement for a multiplex Fourdrinier machine.

As shown on the drawings: Referring to the machine arrangement illustrated in Figure 1, the reference numeral 1 indicates the main machine room floor, while the reference numeral 2 indicates an upper floor. Mounted on the upper floor 2 is an upper Fourdrinier briefly comprising a breast box 3, a deckle mechanism 4 and an upper wire 5. The upper wire 5 passes around a breast roll 6 and over table rolls 7 and wire supporting and guide rolls 8. The wire 5 also passes between a lower couch roll 9 and an upper couch roll 10. An upper pickup felt 11 is trained around upper felt carrying rolls 12 and lower felt carrying rolls 13. The upper felt 11 passes through openings 14 and 15 in the upper floor 2.

Mounted upon the main or lower floor 1 below the upper Fourdrinier is a lower Fourdrinier briefly comprising a breast box 16, a deckle mechanism 17 and a lower wire 18. The lower wire 18 passes around a breast roll 19 and over table rolls 20. The lower wire 18 passes between a lower couch roll 21 and an upper couch roll 22, between which the upper felt 11 also passes. A lower pickup felt 23 is trained around felt carrying rolls 24. The upper felt 11 and the lower felt 23 pass through the nip of a first set of press rolls 25 and 26. The upper felt 11 comes in contact with the lower felt 23 at a point just previous to entering the nip of the press rolls 25 and 26. A second set of press rolls 27 and 28 are provided between the nip of which the upper felt

passes after parting from the lower felt. After leaving the press rolls 25 and 26, the upper felt carries the two webs of paper which have been felted together. The upper press roll 27 has a metal surface to which the paper clings while the felt 11 parts from the paper and returns to the couch rolls 9 and 10 of the upper Fourdrinier. The web of paper is prevented from 10 winding around the roll 27 by a scraper or doctor 29. The web of paper 30 then passes over a smoothing roll 31 and then through the nip of the smoothing rolls 31 and 32 which act to further cement the two webs 15 together and at the same time laying down the fibres and giving a higher finish to the sheet. From the smoothing rolls 31 and 32 the sheet of paper passes through the dryers 33 and calenders which give the 20 finish to the paper.

In the arrangement of the Fourdriniers illustrated in Figure 1, the wires 5 and 18 both travel in the same direction and conduct webs through the nip of the couch 25 rolls 21 and 22 of the lower Fourdrinier. The webs are thus felted together into one sheet and carried through the nip of the press rolls 25 and 26 to be further felted together before being conducted through 30 the press rolls 27 and 28, between the smoothing rolls 31 and 32 and through the dryers 33.

Figure 2 illustrates a modified arrangement of a multiplex paper making machine 35 with the upper Fourdrinier mounted on the main machine room floor 34 and with the second Fourdrinier placed in the basement on the floor 35 and reversed so that the upper wire 36 and the lower wire 37 travel 40 in opposite directions. The two webs of paper, after passing through the respective nips of the upper set of couch rolls 39 and the lower set of couch rolls 40, are brought together at the felt carrying roll 41. In 45 this arrangement the upper web of paper is carried by the upper felt 42 from the upper Fourdrinier, while the lower web of paper is carried by the lower felt 43 from the lower Fourdrinier and the two webs are 50 felted together by passing through the nips of the first set of press rolls 44. The felted webs are carried along by the upper felt 42 through the nip of a second set of press rolls 45 and 46. The upper press roll 45 has a metal surface to which the paper 55 clings, while the felt 42 parts from the paper and returns to the couch rolls 39. From the press roll 45 the felted webs of

paper then pass over a smoothing roll 47 and then between the nip of smoothing rolls 60 47 and 48 which act to further cement the two webs together and at the same time laying down the fibres. The paper next passes through the dryers 49 and calenders which give the desired finish to the paper. This 65 arrangement produces a particularly strong product since the operation of the Fourdrinier parts in opposite directions bring about a crossing and interlacing of the fibers which is very desirable. 70

While two multiplex arrangements have been illustrated and described whereby a plurality of webs of paper from a plurality of Fourdriniers at different levels can be felted or molded together to produce a multiplex sheet of paper, it will of course be understood that many different arrangements of the felts, the couch rolls, the press rolls, and dryers with respect to one another may be used without departing from 80 the principles of this invention. 75

Multiplex sheets of paper of different kinds and quality may be readily produced by the multiplex Fourdrinier arrangement, as well as multiplex paper having different colors on opposite sides. 85

I am aware that numerous details of construction may be varied through a wide range without departing from the principles of this invention, and I, therefore, do not purpose limiting the patent granted otherwise than necessitated by the prior art. 90

I claim as my invention:

1. A multiplex paper making machine comprising a plurality of Fourdriniers mounted one above the other, wires forming part of said Fourdriniers and adapted to run in different directions, couch rolls coacting with each of said Fourdriniers, sets of press rolls, and a plurality of felts coacting with the couch rolls and with the press rolls for removing webs of paper from said Fourdriniers to felt said webs of paper together at the first set of said press rolls. 100

2. In a multiplex Fourdrinier paper machine, the combination with a plurality of Fourdrinier wires running in opposite directions and located at different levels, of a pick-up felt coacting with each wire to remove a web of paper therefrom, and a pair of press rolls for pressing said felts to mould said webs of paper together. 105

In testimony whereof I have hereunto subscribed my name.

HERMAN ELSAS.
